UNITED STATES PATENT OFFICE.

HERMAN JAWORSKI, OF NEW HAVEN, CONNECTICUT, ASSIGNOR TO
SARGENT & CO., OF SAME PLACE.

DESIGN FOR BELL-PULLS.

SPECIFICATION forming part of Design No. 11,635, dated February 3, 1880.
Application filed December 31, 1879. Term of patent 14 years.

To all whom it may concern:

Be it known that I, HERMAN JAWORSKI, of New Haven, in the county of New Haven and State of Connecticut, have invented a new Design for Bell-Pulls; and I do hereby declare the following, when taken in connection with the accompanying drawings and the letters of reference marked thereon, to be a full, clear, and exact description of the same, and which 5 said drawings constitute part of this specification, and represent, in—

Figure 1, front view of the lever; Fig. 2, front view of the plate.

This invention relates to a design for that 15 class of bell-pulls known as "lever-pulls;" and it consists in the configuration of the plate, and also in its ornamentation, as shown in the accompanying illustration.

The body of the plate is in form of a parallelogram with a semicircular projection at top and bottom. At each side is a projection, the side of which is parallel with the side of the body, and at the center of each of these 20 projections is a projection in form of a segment. The face of this plate is ornamented by a plain bead around the outer edge, and

along the side projections is a series of points turned inward. The panel, as also the ends of the segmental projection at the side, is ornamented; but this last ornamentation may 30 be changed without departing from this design.

The lever shown in Fig. 1 is correspondingly ornamented.

I claim—

1. The design for bell-pull plate, consisting of the body in the form of a parallelogram with a semicircular projection at each end and a projection at each side parallel with the sides of the body, and from the center of each 40 of these projections a segmental-shaped projection, as shown in the accompanying illustration. 35
2. The design for bell-pull, consisting of the plate with a border on its face composed of 45 a series of points turned inward, as shown in the accompanying illustration.

HERMAN JAWORSKI.
